UNITED STATES PATENT OFFICE

2,573,866

LEG BRACE

John H. Murphy, Canton, Ohio, assignor of thirty one-hundredths to Myron W. Nusbaum, Canton, Ohio, and thirty one-hundredths to Edward J. McMullen, Memphis, Tenn.

Application May 14, 1948, Serial No. 27,032

4 Claims. (Cl. 128—80)

1

The invention relates to orthopedic braces and more particularly to mechanically operated braces to assist paraplegics in walking.

There are many thousands of cases in the country today where, due to injury to, or disease of, the spine the patient has absolutely no use of his legs, a large number of these cases being casualties of the recent war. As these victims of paraplegia are unable to walk with the assistance of crutches owing to the fact that their legs are entirely paralyzed and will not support the weight of the body, it is customary to attach rigid braces to the legs, so that with the assistance of crutches the wearer can drag or swing his legs between the crutches. This requires that the entire weight of the body is carried suspended from the arm pits upon the crutches, making it a very tiring and painful operation for the patient to move about on crutches.

It is an object of the present invention to provide leg braces adapted to be worn by a person having no use of his legs, the braces having means thereon which will cause the legs to simulate a natural walking movement.

Another object is to provide apparatus of this character in which when the patient lowers his weight upon either leg the mechanically operated mechanism will automatically move the other leg in a walking movement which will be repeated as the weight is shifted to that leg.

A further object of the invention is to provide braces of the character referred to having knee and hip joints which are normally locked in rigid condition and means for automatically unlocking and locking said joints at the proper times during the walking operation.

It is also an object of the invention to provide such braces in which the movement of the joints is limited during the walking operation and in which manual means is provided for unlocking the joints to permit sufficient movement thereof to permit the wearer to assume a sitting position.

A still further object is to provide such braces in which the knee and hip joints are normally locked in rigid condition by spring loaded locking pins controlled by cables connected to the belt or body frame of the braces, whereby when the weight of the wearer is shifted to either leg the knee and hip joints of the other leg braces will be unlocked sufficiently to permit them to be flexed in a walking motion.

Another object is to provide braces of this character in which a spring cylinder mounted above the knee joint of each leg brace, and connected by a cable to the belt or body frame,

2

whereby when the knee and hip joints of either leg are unlocked, that leg will be automatically flexed in a walking motion.

A further object is to provide braces of the character referred to in which as a step is completed with either leg, and the weight of the wearer is returned to that leg, the knee and hip joints of the corresponding leg brace will be automatically locked in rigid condition.

10 It is a still further object of the invention to provide such automatically operated knee and hip joints in an artificial leg.

The above objects together with others which will be apparent from the drawings and following 15 description, or which may be later referred to, may be all attained by constructing the improved leg braces in the manner hereinafter described in detail and illustrated in the accompanying drawings, in which:

20 Fig. 1 is a side elevation of the brace applied to a human body, showing in dotted lines a forward striding position;

Fig. 2 a front elevation of the brace in normal position;

25 Fig. 3 an enlarged sectional view of one of the drop foot connections;

Fig. 4 an enlarged, longitudinal, sectional view of one of the spring cylinders;

Fig. 5 an enlarged fragmentary, longitudinal, 30 sectional view of a portion of one leg brace;

Fig. 6 a transverse sectional view on a still larger scale taken as on the line 6—6, Fig. 5;

Fig. 7 a sectional view also on a larger scale, taken on the line 7—7, Fig. 5;

Fig. 8 a fragmentary sectional elevation of one of the hip joints in the unlocked position to permit flexing of the same to produce a walking motion;

Fig. 9 a similar view of one of the knee joints;

Fig. 10 a sectional elevation of one of the hip joints showing the same entirely unlocked to permit flexing of the same to assume a sitting position; and

Fig. 11 a sectional view through the hip joint taken as on the line 11—11, Fig. 5.

Now referring more particularly to the drawings, in which similar numerals indicate similar parts, the invention is disclosed as applied to a pair of leg braces, attached to a belt or body frame, for use by paraplegics. It should be understood however that the invention is also applicable to a single leg brace for persons having only one paralyzed, or injured leg, and that the invention may be also applied to artificial legs, as well as to leg braces.

The invention as disclosed in the drawings includes a belt or body frame, indicated generally at 15, which may be adjustably strapped around the waist of the wearer, just above the hips, by any suitable means such as the buckle straps 16.

A metal plate 17 may be attached to each side of the belt or body frame 15, as by screws 18, located through the belt 15 and plate 17 and into the studs 19 and 20, which are provided for detachably connecting the leg braces to the belt 10 or body frame as will be later described in detail.

Each leg brace includes the angular support plate, indicated generally at 21, having near one end an aperture 22 for pivotally mounting 15 upon the stud 19 and near its other end the vertically elongated opening 23 received over the stud 20 and permitting a limited pivotal movement of the plate 21 upon the stud 19.

The length of the opening 23 may be adjusted to limit the pivotal movement of the support plate 21 relative to the body frame 15, by means of a pair of set screws 24, threaded through the upper and lower edges of the plate 21 and extending into the ends of the vertical opening 23, for contact with the upper and lower sides of the stud 20 as the support plate is pivotally moved upon the stud 19.

The support plate 21 may be detachably, pivotally mounted upon the studs 19 and 20 by 30 means of a plate 25 having a spaced pair of key hole slots therein, the enlarged portions 26 of the key hole slots being of sufficient diameter to pass over the outer ends of the studs 19 and 20 and the reduced portions 27 of the key hole slots being of sufficient width to fit snugly upon the annularly grooved portions 28 of the studs 19 and 20.

Each of the support plates 21 has at its forward end a downwardly and outwardly disposed 40 arm 29, terminating at its lower end in the substantially vertical ear 30 located adjacent to the hip joint of the wearer and having the substantially vertical notch 31 in its lower edge, communicating at its forward side with the relatively shallow arcuate notch 32. At the rear side of the notch 31 the lower edge of the ear 30 is substantially flat, as indicated at 33.

Each leg brace includes the upper section, indicated generally at 34, extending approximately from the hip joint to the knee joint of the wearer, and the lower section indicated generally at 35, extending from the knee joint to the foot or ankle joint. Each of these leg brace members is preferably formed of metal tubing, substantially oval in cross section.

A spaced pair of ears 36 is formed upon, or attached to the upper end of each upper brace member 34, and the ear 30, at the lower end of the arm 29 of the support plate, is received between the ears 36 and pivoted thereto as by the internally threaded bushing 37 integrally formed upon the nut 38, which is of elongated shape as shown in Figs. 3 and 10, and received in a correspondingly shaped socket 39 in the adjacent ear 36, as shown in Fig. 11.

The screw 40 is threaded into the bushing 37 from the other side of the plate, the head 41 of said screw preferably being seated in a socket 42 in the other ear 36. The bushing 37 not only forms a pivot for the ear 36 but also serves as a spacer to prevent the screw 40 from clamping the ears 36 tightly together upon the ear 30.

The brace member 34 is provided with a longitudinal bore 43, within which is slidably located 75

a locking pin 44 which is normally urged toward the ear 30 by means of a coil spring 45 located within the bore 43 behind the pin. A wire or cable 46 is connected to the locking pin 44 and located through the tubular brace member 34 and around a pulley 47 which is pivoted between a pair of arms 48, formed in the brace member 34, as by the bushing nut 49 and screw 50.

The pulley 47 is provided with two annular grooves 51 and 51a, the wire or cable 46 being located in the groove 51a and fixed to the pulley, intermediate its ends, as by the screw 52. After passing around the pulley 47, the other end of the wire or cable 46 is connected to the stud 20, as by means of a bracket 53, which may be provided with an elongated opening 54 received upon the reduced outer end 55 of the stud 20 in back of the head 56 of said stud.

The end portion of the wire or cable 46 is located through a bore 57 in the boss 58 of the bracket 53 and adjustably connected thereto, as by the set screw 59. In order to limit the movement of the pulley 47 the central flange 60 thereof, which separates the annular grooves 51 and 51a, has an arcuate notch 61 formed therein, and the reduced end 62 of a spring loaded plunger 63 is normally located in said notch by means of the coil spring 64, located in the bore 65 between the plunger 63 and the nut 66.

For the purpose of manually withdrawing the plunger out of the arcuate notch 61, a rod 67 is connected to the plunger and extends upward through the bore. At the lower end of the brace member 34 a spaced pair of ears 68 is provided, similar to the ears 36 above described, and a locking pin 69 is slidably mounted in the bore 70 of said brace member and normally urged downward by means of the coil spring 71, a wire or cable 72 being connected to said locking pin and passing up through the tubular brace member 34 and over the pulley 73, the upper end of the wire 72 being located in the groove 51 of the pulley 47 and fixed thereto as by the screw 52.

The ears 68 are located substantially at the knee joint of the wearer and the other portion of the knee joint of the brace is formed by the ear 74, similar to the ear 30, above described, and formed upon, or attached to, the upper end of the lower brace member 35.

The ear 74 is received between the ears 68 and pivotally mounted therein, as by the bushing nut 75 and screw 76 similar to the bushing nut and screw above described with reference to the hip joint of the brace.

The ear 74 has in its upper side, the relatively deep, narrow notch 77, communicating with the relatively shallow, arcuate notch 78, which notches are similar to the notches 31 and 32 in the ear 30, above described.

The locking pin 69 is normally received into the deep, narrow notch 77 in the same manner that the locking pin 44 is received into the notch 31, to hold the knee and hip joints rigid, at which time the flat upper end 79 of the ear 74 is received against the bottom of the slot between the ears 68 in the same manner that the flat lower end of the ear 30 is received against the bottom of the slot between the ears 36.

With the parts in this position, as shown in Fig. 5, the brace members 34 and 35 will be rigidly locked together in straight condition, as indicated in full lines in Fig. 1.

A spring cylinder 80 is mounted upon the front

side of each of the upper brace members 34, preferably adjacent to the knee joint, and may be adjustably mounted by locating the cylinder through a suitable bore in a boss 81 formed integrally with the brace member 34, a set screw 82 holding the cylinder in adjusted position therein.

A plunger 83 is slidably located within the cylinder 80 and provided at its lower end with a head 84 which may be provided with a leather 85 if desired. A coil spring 86, which has a pull considerably less than the weight of the wearer, is located within the cylinder 80, between the head 84 of the plunger and the cap 87 of the cylinder, which cap is threaded upon the cylinder 15 as indicated at 88 so as to adjust the tension upon the spring.

In order to provide a further adjustment, the upper end of the plunger, above the cap 87, is threaded, as indicated at 89, and the sleeve 90 20 is threaded thereon and connected to the lower end of a cable 91, the upper end of which is adjustably connected to a bracket 92, similar to the bracket 53, which is connected to a stud 93, fixed upon the belt, or body frame, forwardly of the 25 plate 17.

To provide a foot or ankle joint, which will prevent the toe of the foot from dragging upon the floor or ground and hold the foot in substantially horizontal position, a joint member as 30 shown in Fig. 3 is provided. This joint member comprises a stirrup 94 adapted to be attached to the shoe of the wearer, as is common in braces of this general type.

For this purpose the upper end of the stirrup 35 is provided with an ear 95 received between the spaced ears 96 at the lower end of the lower brace member 35. A flat stud or pin 97 is located through the ears 96 to form a pivot for the stirrup 94. The ear 95 of the stirrup is provided with a 40 circular pivot opening 98 communicating with the restricted slot 99 open through the top of the ear 95.

For the purpose of preventing the toe of the foot from dragging a spring pressed plunger 100 45 is slidably mounted in a bore 101 at the lower portion of the brace member 35, a coil spring 102 being inserted between said plunger and the screw plug 103, in the upper end of the bore, so as to normally urge the lower end of the plunger 100 into contact with the substantially flat, upper surface 104 of the ear 95 of the stirrup.

In order to connect the stirrup to the brace member 35 said brace member may be swung backward to substantially horizontal position, so that the flat stud 97 may be inserted through the rectangular slot 99 in the ear 95 of the stirrup, and the stud 97 is moved down into the circular opening 98 of the stirrup and the brace member 35 is swung above to substantially vertical position, as shown in Fig. 3, pivotally mounting the stirrup upon the brace member 35 and preventing accidental removal thereof.

Inside leg braces are provided for each leg comprising the upper and lower inner brace members 106 and 107 respectively, these brace members being similar to the outer brace members above described and connected at the knee joints by hinge members indicated generally at 108. The lower ends of the inside brace members 107 may be detachably connected to the stirrup 94 by joints such as shown in Fig. 3 and above described.

The inner and outer leg brace members are connected together by the usual leather covered metal straps, as indicated at 109, adapted to fit

around the back of the leg, and by the straps 110 and knee pad 111, fitting around the front of the leg.

In the operation of the device, the wearer is of course supported upon crutches, particularly in cases of complete paralysis from the waist down. With the braces mounted upon the wearer, as shown in Figs. 1 and 2, in order to produce a walking motion the weight of the wearer is shifted to the right leg and the left crutch is moved forward, and the body is bent slightly forward and toward the right from the waist, and this results in a pull upon the wire or cable 46 on the left side, which is sufficient to pull the corresponding locking pins 44 and 69 out of the deeper notches 31 and 71 respectively of the hip and knee joints and into the wider arcuate notches 32 and 78, unlocking the hip and knee joints and permitting a limited pivotal movement of the upper and lower brace members 34 and 35 respectively, as shown in Figs. 8 and 9, and the spring cylinder upon that leg then operates, swinging the leg forward in a walking motion as indicated in dotted lines in Fig. 1.

It will be seen that as the body is bent forwardly and toward the right, for instance, placing the weight upon the right leg, the left side of the body frame or belt 15, as viewed in Fig. 5 of the drawing, will be tilted so that the stud 20 will be higher than the stud 19, pulling upon the cables 46 and 72 so as to release the locking pins 44 and 69 of the hip joint and knee joint respectively, withdrawing them from the notches 31 and 71 respectively, permitting the cylinder 80 and associated parts of the left leg brace to pull the same forwardly in a walking motion so that the pivot joints of the hip and knee respectively of that leg assume the positions shown in Figs. 8 and 9 respectively.

The wearer then throws his weight to the left side, putting his weight on the left leg, which has been raised to the dotted line position and leans backward from the waist, releasing the tension on the spring loaded locking pins 44 and 69 on the left side and moving the hip joint back to the position shown in Fig. 5, engaging the locking pin 44 in the deeper notch 31 in the hip joint.

He then puts his right crutch forward and leans forward and to the left, keeping his weight on his left leg, whereby the weight of his body overcomes the pull of the left hand spring cylinder, so that the left knee joint returns to normal, straight position and permits the locking pin 69 to enter the deeper notch 71, locking the left knee joint as shown in Fig. 5 and holding the leg brace on the left side locked in rigid straight position, while the brace on the right leg will be operated as above described to unlock the hip and knee joints thereof and swing the same forward in a walking motion. This operation is repeated as each step is taken.

The pivotal connection of the support plate 21 upon the stud 19, and the elongated opening 23 in the support plate receiving the stud 20, permits a limited forward and backward bending of the body from the waist, during the walking movement.

When the wearer desires to assume a sitting position, the spring loaded plungers 63 are manually pulled upward out of engagement with the notches 61 in the pulleys 47, by means of the rods 67, and the wires or cables 46 are pulled upward manually, rotating the pulleys 47 sufficiently to withdraw the locking pins 44 and 69

entirely from the arcuate notches 32 and 78 so that both of these pivotal joints on each side may be flexed to the desired extent to permit the wearer to assume a sitting position. In Fig. 10 is shown the manner in which the upper or hip joint of each brace may be flexed to a sitting position, and it will be obvious that the knee joints are correspondingly flexed in opposite direction.

I claim:

1. Walking leg braces comprising a body frame adapted for connection to the trunk of the body of a wearer, leg braces, means upon the leg braces for connecting them to the legs of the wearer, means pivotally connecting the upper ends of the leg braces to opposite sides of the body frame, means normally locking the pivots in aligned condition, means operated by the tilting of the body frame forwardly and downwardly to one side for unlocking the pivot on the other side, and means connected to each leg brace and to the body frame for swinging each leg brace in a forward walking motion when the corresponding pivot is unlocked, whereby when said walking leg braces are connected to the body of a person the alternate shifting of the wearer's weight from one leg to the other and simultaneous bending of the wearer's body forwardly and in the direction of said other leg will cause the alternate unlocking of the pivots and swinging of the leg braces in a forward walking motion.

2. Walking leg braces comprising a belt adapted for connection to the trunk of the body of a wearer, leg braces, means upon the leg braces for connecting them to the legs of the wearer, means pivotally connecting the upper ends of the leg braces to opposite sides of the belt, each leg brace having a pivotal knee joint and hip joint therein, spring loaded locking pins for normally locking said pivotal joints in aligned condition, cables connected to said locking pins and to said belt at points to the rear of said pivotally connecting means for unlocking said pivotal joints on either leg brace when the belt is tilted forwardly and downwardly to the other side, and means connected to each leg brace above the knee joint thereof and to the belt for swinging each leg brace in a forward walking motion when the pivotal joints therein are unlocked, whereby when said walking leg braces are connected to the body of a person the alternate shifting of the wearer's weight from one leg to the other and simultaneous bending of the wearer's body forwardly and in the direction of said other leg will cause the alternate unlocking of the pivots and swinging of the leg braces in a forward walking motion.

3. Walking leg braces comprising a belt adapted for connection to the trunk of the body of a wearer, leg braces, means upon the leg braces for connecting them to the legs of the wearer, means pivotally connecting the upper

ends of the leg braces to opposite sides of the belt, each leg brace having a pivotal knee joint and hip joint therein, spring loaded locking pins for normally locking said pivotal joints in aligned condition, cables connected to said locking pins and to said belt at points to the rear of said pivotally connecting means for unlocking said pivotal joints in either leg brace when the belt is tilted forwardly and downwardly to the other side, and means including a cylinder mounted upon each leg brace above the knee joint, a spring loaded plunger in the cylinder and a cable connecting said plunger to the belt for swinging each leg brace in a forward walking motion when the pivotal joints therein are unlocked, whereby when said walking leg braces are connected to the body of a person the alternate shifting of the wearer's weight from one leg to the other and simultaneous bending of the wearer's body forwardly and in the direction of said other leg will cause the alternate unlocking of the pivots and swinging of the leg braces in a forward walking motion.

4. Walking leg braces comprising a belt adapted for connection to the trunk of the body of a wearer, depending brackets pivotally connected to opposite sides of the belt, leg braces, means upon the leg braces for connecting them to the legs of the wearer, each leg brace having a pivotal hip joint connecting them to the corresponding bracket and a pivotal knee joint, spring loaded locking pins for normally locking said pivotal joints in aligned condition, cables connected to said locking pins and to said belt at points to the rear of said pivoted brackets for unlocking said pivotal joints on either leg brace when the belt is tilted forwardly and downwardly to the other side, and means connected to each leg brace above the knee joint thereof and to the belt for swinging each leg brace in a forward walking motion when the pivotal joints therein are unlocked, whereby when said walking leg braces are connected to the body of a person the alternate shifting of the wearer's weight from one leg to the other and simultaneous bending of the wearer's body forwardly and in the direction of said other leg will cause the alternate unlocking of the pivots and swinging of the leg braces in a forward walking motion.
